CONTINUOUSLY OPERATING CUT OFF
MECHANISMS

Karl Sieg, Philadelphia, Pa., assignor to Samuel M. Langston Company, Camden, N. J., a corporation of New Jersey

Application June 5, 1933, Serial No. 674,311

19 Claims. (Cl. 164—43)

This invention relates to machines for cutting into sections continuously delivered sheet material, and more particularly to a control and driving mechanism for that type of cut-off mechanism in which the knives are in continuous movement, and in their cutting phases come together and then separate while traveling with the material.

For cutting comparatively stiff material, such as double-faced corrugated board, it is important that the rate of travel of the cutting knives in the general direction of movement of the material at the time of cutting action, be substantially the same as the rate of travel of the material.

If it is desired to maintain the feeding of the sheet material constant regardless of changes in the lengths of sections cut, then it is necessary to vary the total time of the cycle of movement of the cut-off mechanism, so that the frequency of operation of the knives will be inversely proportional to the lengths of sections cut. Each such change in the total time period of the cycle of the cut-off mechanism changes the speed at the time of cutting, and requires readjustment of the relative rates of speed of the different parts of the cycles of the cutter, so as to again make the speed of the cutting knives, at the time of cutting action, correspond to the speed of the material.

One object of the present invention is to provide improved means for securing a travel of the cutter at the same speed as the sheet, even though the time period of the cycle of movement of the knife be varied to cut longer or shorter sections from the sheet traveling at any given speed.

Another object is to secure an increase in the range between the longest and shortest section which may be cut from a continuously advancing sheet by means of a continuously running cutter.

A further object is to permit very small adjustments to be made in the operation of the cut-off mechanism, so that the sections cut may be made to vary by very small increments.

In carrying out my invention, I employ a differential gearing between the drive and the cut-off mechanism, and I vary the speed of the cutting knives in their cycles of operation by varying the position of one or more of said gears.

As a feature of the invention, I provide a manually operable means for controlling the range of movement of said movable gear or gears, so that said differential will operate to conform with the adjustment of the total cycle of frequency of operation of the cut-off mechanism. The differential gearing may be used alone to effect the desired variations in the speed of the cutting knives, or,

if desired, may be used in conjunction with a pair of elliptical gears. By means of this arrangement, I am able to obtain a wider range of variation between the longest and shortest section. Also I may vary the speed of the cycle of operation of the cutting knife so that at any point in the cycle, the cutting knives may be almost at a standstill. This operation may be advantageous for cutting long sections.

Various other objects, advantages, and important features will be hereinafter pointed out or will be apparent from a consideration of the specific construction illustrated in the accompanying drawings which constitute two of the many possible embodiments of the invention hereinafter claimed.

In these drawings:

Fig. 1 is a side elevation of the machine.

Fig. 2 is a horizontal section of the machine.

Figs. 3 and 4 are sections taken on the line 3—3 and 4—4 respectively of Fig. 2.

Fig. 5 is a somewhat diagrammatic showing of a part of the gearing shown in Fig. 3.

Fig. 6 is a side elevation of a portion of another form of transmission between the drive and the cut-off mechanism.

Fig. 7 is an end view of the construction shown in Fig. 6, and

Fig. 8 is a section taken on the line 8—8 of Fig. 6.

In the traveling cut-off or flying shears illustrated there is employed a type of a pair of up-standing arms 10 pivoted at opposite sides of the machine on a transverse rock shaft or pair of pivot pins 11, and connected at their upper ends by a transverse beam 12 which carries the lower knife or cutting member 13. Each arm 10 carries a pivot pin 14 on which is mounted a lever 15, the two levers, at their upper front ends, carrying a transverse beam 16 on which is mounted the upper knife or cutter 17. The arms 10 extend substantially vertically, so that the knife 13 swings back and forth substantially horizontally and approximately in the path of travel of the sheet.

The knives 13 and 17 are approximately the same distance from the pivot pins 14, so that as the levers 15 are operated, the knife 17 moves up and down, and cooperates with the lower knife to give a shear cut. For driving the knives and their carrying members, there is provided a transverse shaft 20 having cranks 21 at opposite ends thereof, carrying crank pins 22 mounted in the ends of the levers 15. Thus, as the shaft 20 is rotated, the lower rear ends of the levers 15 are caused to travel in a circular path, and the front

5

30

35

40

45

50

55

upper knife 17 travels in a substantially elliptical path. As the members which carry the two knives are connected by the pin 14, the rotation of the crank imparts a back and forth movement 5 of the lower knife in the direction of travel of the sheet. This construction is illustrated and broadly claimed in my prior Patent 1,359,076.

The arms 10 may be forked adjacent to their 10 upper ends so that said ends lie in planes at opposite sides of the arms 15. Thus the arms 15 lie in the same plane as the lower portions of the arms 10.

The sheet feeding mechanism comprises a pair 15 of feed rollers 24 and 25, the lower feed roller 25 being driven from the main source of power. For instance, it may be provided with a gear 26 driven through a series of gears 28, 29 and 30 from the main drive shaft 27. The upper roller 24 may be freely rotatable or may be positively driven 20 from the roller 25 by a train of gears as shown.

For driving the cut-off from the shaft 27 there 25 is provided a train of gearing including means for selectively varying the frequency of operation of the cut-off mechanism. As shown a variable speed transmission 32 is driven by the drive shaft 27 and is of the ordinary type in which two pulleys, each including a pair of opposite conical discs, are provided, with a belt therebetween for transmitting power. The effective diameter of the pulleys may be altered by moving the conical discs of one or both pairs toward and from each other. The details of this mechanism 30 are not shown as it may be of any standard design, such as that known in the trade as the P. I. V. or the Reeves drive, or may constitute a speed 35 change device of the gear type.

As an important feature of the present invention, the drive connection between the variable transmission 32 and the operating shaft 20 of 40 the cut-off mechanism includes a differential gearing which is so automatically operated during each cycle of operation of said mechanism as to vary the speed ratio of said gearing and consequently vary the relative rates of speed of the 45 cut-off mechanism in its cycle. By "differential gearing" I mean a gearing in which one of the gears is bodily movable to change the speed ratio of the gearing. This differential gearing is driven by a pinion 58 on the output shaft 33 of the 50 variable speed transmission 32 and meshing with the spur gear 59 mounted on a counter shaft 60. The shaft 60 has a spur gear 61 which meshes with the external teeth of an annular gear 62 carried on a sleeve 63 supported by suitable bearings on a 55 shaft 56 so that said gear 62 will be rotatable with respect to said shaft 56. The shaft 56 has secured thereto a gear 64 concentric with the gear 62 and driven from the annular gear 62 by one or more differential pinions 65 meshing with said gear 64 and the internal teeth of the annular gear 62. Three of such differential pinions are shown 60 spaced 120° apart to effect a balanced arrangement. By means of this train of circular gears, when the axes of the differential pinions 65 are 65 stationary, the speed ratio between the shafts 56 and 33 will be constant. The shaft 56 drives the crank shaft 20 of the cutter through a pair of elliptical gears 100, 101.

In case the elliptical gears are not employed, a 70 single shaft may be used in place of the shafts 20 and 56. That is, the shaft 56 may be the crank shaft or the differential may be on the shaft 20. If a rotary type of cut-off be used, the shaft 20 will 75 not be a crank shaft and one of the cutters may

be on the shaft 20 or an extension thereof, or on an extension of the shaft 56.

Means are provided for oscillating the differential pinions 65 bodily during each cycle of 5 operation of the cut-off mechanism, in order to vary the speed ratio between the drive shaft 33 and the shaft 56. For that purpose, the differential pinions 65 are journaled to a flange 66 of a sleeve 67 which encircles the shaft 56, and which is supported thereon for rotation with respect 10 thereto by suitable bearings.

In the form shown in Figs. 1 to 5, this sleeve 15 67 is oscillated by linkage means driven from the shaft 60. This includes an arm 68 having one end connected to said sleeve and the other end pivoted to one end of a connecting rod or link 70. The intermediate portion of the link 70 is pivotally connected to one end of a link 71, the other end of said link 71 being pivotally connected to a crank on a crank arm 69 secured to the shaft 60. 20 As the shaft 60 rotates, it will operate the linkage between this shaft and the sleeve 67 and thereby oscillate the differential pinions 65 bodily.

The variation in operation of the differential 25 gearing is effected by permitting controlled movement of the other end of the link 70. For that purpose, said end of the link 70 is pivoted to a block 73 slidably mounted on a guide 72. As the shaft 60 rotates, the link raises and lowers and at the same time moves endwise. The block 73 30 slides in the guide 72 and serves to limit the movement of the link 70 so that the angle of oscillation of the arm 68 is correspondingly limited.

By varying the position of the guide the movement of the link 70 may be such that for any 35 frequency of operation of the cut-off, the differential will cause the knives to travel at the same speed as the traveling material at the instant of cutting.

In the specific form shown, the guide 72 is angularly adjusted to effect this control. It extends 40 diametrically of a normally stationary member 74 preferably in the form of a worm wheel meshing with a worm 75 which may be rotated to bring the guide 72 at any desired angle in respect to the 45 general direction of the length of the link 70. The worm wheel is supported in a housing 74a having bearing surfaces 74b engaging annular shoulders formed at the ends of said worm wheel.

The variable speed transmission 32 is adjustable 50 to effect changes in the frequency of operation of the cut-off in respect to the speed of travel of the sheet, and the guide 72 may be adjusted to make the speed of travel of the cutter, when cutting, substantially the same as the speed of 55 the sheet. As one important feature of the invention there is provided a single member for controlling both the variable speed transmission and the differential gearing, so that when adjusting to give any desired length of cut-off section, 60 the speed of the knives in their cycle will be correspondingly adjusted.

Such a single control member is shown as a 65 control shaft 41. As shown it drives a counter shaft 41a through a pair of gears 41b, and the counter shaft 41a has a sprocket wheel 42 which serves, through a chain 42a, to drive a sprocket wheel 43 on the speed ratio control shaft 44 of the variable speed transmission 32. The rotation 70 of this shaft 44 effects a change in the speed ratio between the output shaft 33 and the input shaft 27 to selectively vary the frequency of operation of the cut-off in accordance with the length of section desired. For rotating the shaft 41 there 75 is provided a spindle 35 carrying a hand wheel 36

at one end thereof and a sprocket wheel 37 at the other end thereof. Through a chain 38, this sprocket 37 drives a sprocket wheel 40 connected to the control shaft 41.

5 In order that the operator may move the control hand wheel 36 the proper extent to give any desired length of section, there is provided a calibrated indicating mechanism. This mechanism includes a fixed stud 46 supported on a bracket 10 45 and loosely carrying a dial gear 47 having a hub 48 which cooperates with a braking mechanism 49 by means of which the position of said dial gear may be set at any fixed point. Secured to said dial gear 47 is an indicating dial 50, the rim 15 of which carries a series of section length graduations indicatively cooperating with a pointer (not shown). Meshing with the dial gear 47 is a pinion 51 connected to the control shaft 41.

In the connection between the control shaft 41 20 and the worm 75, compensating means must be provided so that the worm wheel 74 is rotated a proper amount to give the proper effect for each change in the speed ratio of the variable speed transmission. For that purpose, the worm 75 is 25 driven from the shaft 41 through a pair of intermeshing cam gears 76 and 77. The cam member 77 is driven from the control shaft 41 by any suitable means, as for instance by a chain 78 passing around the sprocket 79 on the shaft of said 30 cam gear, and around a sprocket 80 connected to the control shaft 41. For rotating the worm 75 from the cam gear 76 the shaft of said gear has connected thereto a gear 81 meshing with a gear 82 connected to the shaft of the worm 75.

35 The rotation of the worm 75 causes a corresponding rotation of the worm wheel 74, and changes the angular position of the guide 72. This adjustment causes a corresponding change in the movement of the free end of the link 70, 40 so that the movement transmitted to the arm 68 is correspondingly modified. Both adjustments in the variable speed transmission and the differential gearing may be made while the machine is running. The worm wheel 74 is locked by the 45 worm 75 in adjusted position.

In Figs. 6 to 8 there is shown another form of link mechanism for bodily oscillating the differential pinions 65 during one cycle of operation of the cut-off mechanism. In this form, there 50 is provided an arm or yoke 83 connected intermediate its ends to a rock shaft 84 suitably journaled. This arm 83 is oscillated about the axis of the shaft 84 by means of a link 85 pivotally connected at one end to the outer end of the 55 crank arm 69 and at the other end to a bracket 86 extending from said arm 83. The oscillatory movement of the arm 83 effected through the operation of the shaft 60, is transmitted to the arm 68 by means of a link 87 pivotally connected 60 at one end to the outer end of the arm 68 and having the other end thereof pivotally connected to a block 88 supported on the arm 83. The latter end of the link 87 is advantageously bifurcated and has the spaced prongs thereof disposed on opposite sides of the arm 83 and connected to a pivot pin 89. The rock shaft 84 is connected to the arm 83 by means of a bracket 90 extending from a flange 91 at one end of the rock shaft 84 and spaced from the prongs of the 65 link 87 to permit free movement of said link.

The extent of angular oscillation of the arm 68 depends on the position of the block 88 from the axis of the rock shaft 84. In the position shown in Figs. 7 and 8, the link 87 is in neutral 70 position with the block 88 in axial alignment

with the rock shaft 84, so that the oscillatory movement of the arm 83 is not transmitted to the link 87.

In order to selectively move the block 88 in 5 adjusted position so as to obtain the desired movement of the arm 68, the arm 83 is provided with a pair of spaced parallel guides 95, the block 88 being mounted for slideable movement along said guides. Extending longitudinally between these guides 95 and having a threaded engagement with the block 88 is a screw 96, the rotation of which causes the movement of the block 88 along the guides 95 into selective positions away from the axis of the rock shaft 84. This rotation of the screw 96 may be effected from the control shaft 10, 15 41, or may be effected through an independent control. In the specific form shown, this screw 96 is independently controlled by means of a hand wheel 97 connected to one end of the screw. The guides 95 may be provided with a series of 20 calibrations which cooperate with markings on the block 88 so that adjustments may be made to conform with the adjustments in the variable speed transmission 32.

The differential gearing and the linkage for 25 varying the speed ratio thereof may be so constructed as to obtain the desired speed variation in the cycle of operation of the cut-off mechanism without any additional speed varying device. However, from a standpoint of efficient design 30 the guides 72, in the form shown in Figs. 1-5, and the guides 95, in the form shown in Figs. 6-8 are not intended to give the full range of adjustment in the form shown as they may be supplemented by the pair of intermeshing elliptical 35 gears 100 and 101 in the transmission between the drive and the cut-off mechanism.

The elliptical gears 100 and 101 and the differential gearing operate in series, the elliptical gears being fixed with respect to the drive, and 40 both the elliptical gears and the differential gearing combining to drive the cutter at a speed varying in the cycle of operation of the cut-off mechanism, so that the speed of the latter at the instant of cutting will be maintained substantially 45 the same as that of the sheet for any given speed of sheet irrespective of the lengths of the sections into which the sheet is cut.

The gear wheels of the differential gearing are 50 advantageously so proportioned that the shafts 60 and 56 will rotate at the same angular velocity when the axes of the differential pinions 65 are stationary. For instance, the gear 61 has a pitch diameter one-half the external pitch diameter of the annular gear 62, and the gear 64 55 has a pitch diameter one-half the internal pitch diameter of said annular gear.

When the arm 68 is moving in the same angular direction as the annular gear 62, the speed 60 of the gear 64 is less than its normal speed, and when the arm is moving in the opposite direction the speed of the gear 64 is greater than its normal speed. The rate of speed variation of the gear 64 depends upon the angular velocity of the arm 68.

For adjusting the operation of the linkage in order to change the relative rates of speeds in the cycle of operation of the cut-off mechanism, to 65 conform with the change in frequency of operation of the cut-off, I may employ means independent of that which controls the frequency of operation of the cut-off mechanism. In other words, there may be two independent control members.

Having thus described my invention, what I 75

- claim as new and desire to secure by Letters Patent is:—
1. An apparatus for subdividing continuously advancing sheet material transversely into sections, including a cut-off mechanism movable substantially in the same direction as the material at the instant of cutting, a differential gearing for imparting continuous movement to said cut-off mechanism, means for automatically operating said gearing during each successive cycle of operation of said cut-off mechanism for varying the speed ratio of said differential gearing during each of said cycles, and means operable while the machine is running for adjusting said operating means to modify the variation in speed ratio of said differential gearing during each of said cycles. 5
  2. An apparatus for subdividing continuously advancing sheet material transversely into sections, including a cut-off mechanism, a differential gearing for operating said cut-off mechanism, means for automatically operating said differential gearing during each successive cycle of operation of said cut-off mechanism for varying the speed ratio of said gearing during each of said cycles, adjustable means for varying the frequency of operation of the cut-off mechanism to vary the length of sections being cut, and means automatically operable upon the adjustment of said last mentioned means for adjusting said first mentioned means to modify the variation in speed ratio of said differential gearing during each cycle of operation of said cut-off mechanism in accordance with the change in frequency of operation of said cut-off mechanism. 10
  3. An apparatus for subdividing continuously advancing sheet material transversely into sections, including a cut-off mechanism movable substantially in the same direction as the material at the instant of cutting, a drive shaft, a driving connection between said shaft and said cut-off mechanism, and including a variable speed transmission for varying the frequency of operation of said cut-off mechanism in accordance 15 with the length of the sections desired, a differential gearing, and means for operating said differential gearing during each successive cycle of operation of said cut-off mechanism for varying the speed ratio of said gearing during each of said cycles, means for adjusting said variable speed transmission for determining the length of the sections while the apparatus is running, and means for adjusting said differential gearing to modify the variation in speed ratio of said gearing during each cycle of operation of said cut-off mechanism while the apparatus is running so as to maintain the speed of travel of said cut-off mechanism substantially the same as that of the material at the instant of cutting operation. 20
  4. An apparatus for subdividing continuously advancing sheet material transversely into sections, including a cut-off mechanism movable in the same direction as the material at the instant of cutting, a shaft, a power transmitting mechanism between said shaft and said cut-off mechanism for imparting continuous movement to said cut-off mechanism, a drive shaft substantially parallel to said first shaft, a differential gearing between said shafts, and means automatically operated from said drive shaft during each cycle of operation of said cut-off mechanism for bodily oscillating one or more of the gears of said gearing for varying the speed ratios between said drive shaft and said cut-off mechanism during each of said cycles. 25
  5. An apparatus for subdividing continuously advancing sheet material transversely into sections, including a cut-off mechanism movable in the same direction as the material at the instant of cutting, a shaft, a power transmitting mechanism between said shaft and said cut-off mechanism for imparting continuous movement to said cut-off mechanism, a driving shaft transversely spaced from said first mentioned shaft, a differential gearing between said shafts, a crank connected to said driving shaft, and means operated from said crank for bodily oscillating one of the gears of said gearing to vary the speed ratio between said shafts. 30
  6. In combination, a cut-off mechanism, driving means therefor, including a differential gearing, and means including a linkage for automatically operating said differential gearing during each cycle of operation of said cut-off mechanism for varying the speed ratio of said gearing, and means for adjusting said linkage while the machine is running to vary the speed ratio of said gearing during each cycle of operation of said cut-off mechanism. 35
  7. In combination, a cut-off mechanism, driving means therefor, including a drive shaft, a driven shaft, a differential gearing between said shafts, and a linkage between said drive shaft and one of the gears of said gearing for oscillating said gear bodily from said drive shaft during each cycle of operation of said cut-off mechanism, a guide for a portion of said linkage along which said portion slides during each cycle of operation of said differential gearing, and means for changing the position of said guide to effect 40 adjustments in the operation of said linkage. 40
  8. In combination, a cut-off mechanism, driving means therefor, including a drive shaft, a driven shaft, a differential gearing between said shafts, and a linkage between said drive shaft and one of the gears of said gearing for oscillating said gear bodily from said drive shaft during each cycle of operation of said cut-off mechanism, a rotatable member, a guide in said rotatable member for a portion of said linkage 45 whereby said portion slides along said guide during each cycle of operation of said linkage, and means for rotating said member to change the angular position of said guide, whereby the operation of said linkage is modified. 50
  9. In combination, a cut-off mechanism, driving means therefor, including a drive shaft, a driven shaft, a differential gearing between said shafts, a linkage between said drive shaft and one of the gears of said gearing for oscillating said 55 gearing bodily from said drive shaft during each cycle of operation of said cut-off mechanism, a gear wheel, a guide mounted diametrically on said gear wheel for a portion of said linkage, and an irreversible gearing for rotating said gear wheel to effect angular adjustments in the position of said guide, and for locking said gear wheel in adjusted position. 60
  10. In combination, a cut-off mechanism, driving means therefor, including a drive shaft, a driven shaft, a differential gearing between said shafts, and a linkage between said drive shaft and one of the gears of said gearing for oscillating said gearing bodily from said drive shaft 65 during each cycle of operation of said cut-off mechanism, and including a rock shaft, an arm connected to said rock shaft, said arm being provided with a guide, a link having a portion thereof in said guide, and means for oscillating said 70
  - 75

arm from one of said shafts to cause corresponding movement of said link.

11. In combination, a cut-off mechanism, driving means therefor, including a drive shaft, a driven shaft, a differential gearing between said shafts, a linkage between said drive shaft and one of the gears of said gearing for oscillating said gearing bodily from said drive shaft during each cycle of operation of said cut-off mechanism, and including a rock shaft, an arm connected to said rock shaft, said arm being provided with a guide, a link having a portion thereof in said guide, and means for adjusting the position of said link in said guide to modify the operation of said link.

12. In combination, means for feeding a continuous sheet of material at substantially constant speed, a cut-off mechanism for subdividing the sheet into sections, including a crank shaft, a member mounted to move back and forth in the same path substantially parallel to the direction of feeding movement of the material to be cut, a second member pivotally connected to the first mentioned member and to the crank of said crank shaft, a pair of cooperating cutters carried by said members, a drive shaft, a power transmitting mechanism between said drive shaft and said crank shaft, and including a differential gearing, means for automatically bodily moving one gear of said differential gearing during each cycle of operation of said cutters to vary the speed ratio of said differential gearing during each of said cycles, and means operable while the machine is running for varying the extent of said bodily movement.

13. In combination, means for feeding a continuous sheet of material at substantially constant speed, a cut-off mechanism for subdividing the sheet into sections, including a crank shaft, a member mounted to move back and forth in the same path substantially parallel to the direction of feeding movement of the material to be cut, a second member pivotally connected to the first mentioned member and to the crank of said crank shaft, a pair of cooperating cutters carried by said members, a drive shaft, a power transmission mechanism between said drive shaft and said crank shaft for continuously rotating said crank shaft, and including a differential gearing, means for automatically bodily moving one gear of said differential gearing during each cycle of operation of said cutters to vary the speed ratio of said differential gearing during each of said cycles, and means operable while the machine is running for varying the extent of said bodily movement.

14. A machine for subdividing material into sections, including means for advancing a continuous sheet of material at a substantially uniform speed, a pair of cutters movable back and forth in the general direction of the travel of the material, a crank shaft for operating said cutters, a drive shaft, a power transmitting mechanism between said drive shaft and said crank shaft, and including a differential gearing, means for automatically bodily moving one gear of said differential gearing during each cycle of operation of said cutters for varying the speed ratio of said differential gearing during each of said cycles, and means operable while the machine is running for varying the extent of said bodily movement.

15. A machine for subdividing material into sections, including means for advancing a continuous sheet of material at a substantially uniform speed, a pair of cutters movable back and

forth in the general direction of the travel of the material, a crank shaft, for operating said cutters, a second shaft parallel to said crank shaft and transversely spaced therefrom, a drive for said latter shaft, power transmitting means between said latter shaft and said crank shaft, and including a differential gearing, means for automatically bodily moving one gear of said differential gearing during each cycle of operation of said cutters for varying the speed ratio of said differential gearing during each of said cycles, and means operable while the machine is running for varying the extent of said bodily movement.

16. An apparatus for subdividing continuously advancing sheet material transversely into sections, including means for advancing said material at a substantially uniform speed, a cut-off mechanism movable substantially in the same direction as the material at the instant of cutting, a pair of intermeshing elliptical gears for driving said cut-off and varying the speed thereof in its cycle, a differential gearing for driving one of said elliptical gears, and means for automatically operating said differential gearing during each cycle of operation of said cut-off mechanism for modifying the speed variation imparted to said cut-off by said elliptical gears.

17. An apparatus for subdividing continuously advancing sheet material transversely into sections, including means for advancing said material at a substantially uniform speed, a cut-off mechanism movable substantially in the same direction as the material at the instant of cutting, a pair of intermeshing elliptical gears for driving said cut-off and varying the speed thereof in its cycle, a train of circular gears in series with said elliptical gears, and means for bodily moving one gear of said train of gears back and forth during each cycle of operation of said cut-off mechanism for modifying the speed variation imparted to the cut-off mechanism by said elliptical gears.

18. An apparatus for subdividing continuously advancing sheet material transversely into sections, including means for advancing said material at a substantially uniform speed, a cut-off mechanism movable substantially in the same direction as the material at the instant of cutting, a pair of intermeshing elliptical gears for driving said cut-off and varying the speed thereof in its cycle, a train of circular gears in series with said elliptical gears, means for bodily moving one gear of said train of gears back and forth during each cycle of operation of said cut-off mechanism for modifying the speed variation imparted to the cut-off mechanism by said elliptical gears, and means manually operable while the machine is running for varying the extent of said back and forth movement.

19. An apparatus for subdividing a continuous web of stiff sheet material transversely into sections, including feeding means for continuously delivering said web, a cut-off mechanism movable at the instant of cutting in substantially the same direction as said web, a drive shaft, driving connections between said shaft and said feeding means for operating the latter at a substantially uniform speed, and driving connections between said shaft and said cut-off mechanism for imparting a continuous movement to the latter, said last mentioned connections including a variable speed transmission for varying the average or mean speed of said cut-off mechanism in its cycle, and thereby varying the cutting operation of said cut-off mechanism in accordance with the length of section desired, and means for varying

the speed of said cut-off mechanism in its cycle, transmission being adjustable while the apparatus is running, for varying the length of the cut-off sections and maintaining the speed of the cut-off mechanism at the instant of cutting substantially the same as that of the web. 5

KARL SIEG.
